RADIAL FLOW TURBINE

Ragnar Olov Jacob Möller, Finspong, Sweden

Application July 26, 1935, Serial No. 33,371
In Sweden June 6, 1934

5 Claims. (Cl. 253—16.5)

This invention relates to radial flow elastic fluid turbines of the double rotation type. When turbines of this type are arranged as bleeding turbines, the bleeding has hitherto taken place through apertures formed in the turbine discs as well as in the plates of the labyrinth packings situated outside said discs. Out of regard to strength it has not been practicable, however, to form too many and too large apertures in the turbine discs and this fact, in its turn, has restricted in a very high degree the amount of elastic fluid, as steam or gas, which could be bled as a maximum. In order to enable an increased bleeding it has been proposed to arrange an outer part or section of the blading for single rotation by substituting for the outer part or section of one rotary turbine disc a stationary wall carrying guide blades. By this arrangement it was possible to provide between said stationary wall and the adjacent inner turbine disc an arbitrarily ample space through which the elastic fluid can be bled in any quantity desired. In this case there may be provided a regulating element in the blade passage proper between the double rotation and the single rotation sections of the blading. In a turbine of this type, however, the two oppositely rotating shafts or journals will deliver unequally large powers due to the fact that one turbine disc carries fewer blade rings than the other turbine disc. If it is desired to cause the two shafts to deliver equally large powers which is, as a rule, the case, especially in respect of turbines the shafts of which are directly coupled to electric current producers, there must be arranged an auxiliary turbine in connection with one shaft.

The present invention has for its object to provide a radial flow turbine which is of the double rotation type to its whole extent and which allows, nevertheless, the bleeding of any desired quantities of driving fluid without interfering with the strength of the turbine discs.

The invention is characterized, chiefly, by the fact that one of the oppositely rotating turbine discs comprises two or more separate annular sections connected together by means of the moving blade rings carried thereby, inasmuch as the outermost blade ring of an inner disc section and the innermost blade ring of the adjacent outer disc section are connected together on the side of the passage between the blades remote from the disc sections, so that while maintaining double rotation of the whole blade system, bleeding openings of any desired radial width

which extend uninterruptedly all around may be provided on one side of the turbine to permit extraction of driving fluid from one or more spaces formed in the blade system, a regulating element carrying sealing fins being provided in said space or in each of them in order to control the admission of driving fluid to the section of the blade system surrounding the space. 5

In the accompanying drawing, Fig. 1 is an axial section of part of a turbine according to one embodiment of the invention. Fig. 2 is a detail view. Figs. 3 and 4 are axial sections of certain parts of modified embodiments.

With reference to Fig. 1, the numerals 1 and 2 indicate the shafts of the turbine rotating in opposite directions. Shaft 1 carries a turbine disc 3 and shaft 2 carries a turbine disc 4 the diameter of which is greater than that of disc 3. The turbine disc 3 and the corresponding portion of the turbine disc 4 carry blade rings 5 to which driving fluid is admitted in the usual way from chambers 6 of driving fluid chests through apertures 7 formed in the turbine discs. The blade rings 5 form an inner blading surrounded by an outer blading 8 separated from the inner blading 5 by a space 9 of comparatively great radial width. The outer blading 8 is carried, in part, by the outermost portion of the turbine disc 4 and, in part, by a separate turbine disc 10. Said last-mentioned disc is connected to the turbine disc 3, inasmuch as the outermost blade ring 11 of the inner blading 5 which is carried by disc 3 and the innermost blade ring 12 of a blading 8 which carries disc 10 are connected together on the side of the passage between the blades remote from the disc sections 3 and 10. This connection is shown in Fig. 1 as represented by a radially extending annular wall 13 formed integrally with the right hand supporting rings of said two blade rings. 15 20 25 30 35 40

The space 9 between the two bladings 5 and 8 communicates by a corresponding space between the two disc sections 3 and 10 with a bleeding chamber 14 provided in the turbine casing, said connecting space extending uninterruptedly all around. Leading from said bleeding chamber 14 is a bleeding pipe 15. Outside the turbine disc sections 3 and 10 there are labyrinth packings 16, 17, respectively, of which the former leads to chamber 14. Outside the turbine disc 4 there is a labyrinth packing 18. Due to the fact that the connection between the space 9 and the bleeding chamber 14 is open all around, any desired fraction of the driving fluid which has passed the inner blading 5 may be discharged. 45 50 55

In order to regulate the quantity of driving fluid to be allowed to pass also through the outer blading 8, there is provided in the space 9 a throttling element as, for instance, in the form 5 of a cylindrical regulating ring 19. This throttling element may be arranged to effect either a mere throttling regulation or a partial regulation. The regulation is effected in the case of the throttling element shown in the drawing by 10 an axial displacement of ring 19. To this end there may be provided by the side of the ring 19 another ring 20 connected to the regulating ring 19 by means of an expansion ring 21, said ring 20 being capable of axial displacement controlled 15 by a pin 23 rotatably mounted in the turbine casing which is provided with a handle 22, the connection between said pin 23 and the ring 20 being effected by a lever 24 (Fig. 2). The regulating ring 19, for the sake of sealing, may be 20 provided with sealing fins to cooperate with the supporting rings of the blade ring 12 as well as with the turbine disc section 10.

In Fig. 1, I have shown how to effect bleeding also on the side of the turbine remote from the 25 bleeding chamber 14. To this end, the connecting disc 13 is formed with apertures 26, corresponding bleeding passages 27 being formed in the disc 4 as well as in the labyrinth packing 10.

In Fig. 3 I have shown how to connect the two 30 blade rings 11 and 12 by means of an annular disc 25 which is not formed integrally with the supporting rings of the blade rings 11 and 12, but attached thereto by a rolling operation. Instead of a rolling operation for effecting said attachment there may be used bolts or the like.

In Fig. 4, on the contrary, a connection is 35 shown which corresponds to that shown in Fig. 1 with the exception that the connecting disc 13 between the blade rings 11 is unapertured. In 40 Fig. 4 I have further shown an annular member 28 situated between the inner periphery of the disc 10 and the regulating ring 19 which is carried by the stationary plate of the labyrinth packing 17. The object of this annular member 28 is 45 to improve the sealing effect and to this end the regulating ring 19 carries additional sealing fins to cooperate with the member 28, as shown.

In addition to the bleeding device above described, the turbine, may, as shown in Fig. 1, be 50 provided with bleeding and overload passages of well-known character comprising apertures formed in the turbine discs and in the plates of the labyrinth packings as well.

What I claim is:—

55. 1. In an elastic fluid turbine, two turbine discs for opposite rotation and blade rings carried by said discs so as to form a radial flow blading for double rotation, one of said discs comprising a plurality of axially spaced annular sections, the outermost blade ring of an inner disc section being directly connected with the innermost blade ring of the adjacent outer disc section on the side of the blade rings remote from the disc sections, so that said outer disc section is carried by said 60 innermost blade ring, thereby allowing bleeding openings of any desired radial width extending uninterruptedly all around to be provided between said disc sections for the extraction of elastic fluid from a stage of the blading without interfering with the double rotation of the whole blading.

2. In an elastic fluid turbine, two turbine discs for opposite rotation, blade rings carried by said discs so as to form a radial flow blading for 75 double rotation, one of said turbine discs com-

prising two or more separate annular sections spaced radially so as to form an annular opening extending uninterruptedly all around between the outer periphery of an inner disc section and the inner periphery of the adjacent outer disc 5 section, a connection between the outermost blade ring of an inner disc section and the innermost blade ring of the adjacent outer disc section on the side of said blade rings remote from the disc sections, a radial space being provided between 10 said two blade rings in register with said opening, and a regulating element in said space to control the admission of elastic fluid to the blade ring surrounding the space.

3. In an elastic fluid turbine, two shafts for 15 opposite rotation, a turbine disc on each shaft, blade rings on said discs so arranged as to form a radial flow blading for double rotation, one of said turbine discs comprising two separate annular sections spaced radially so as to form an 20 annular opening extending uninterruptedly all around between the outer periphery of the inner disc section and the inner periphery of the outer disc section, a substantially radially extending annular disc connecting the outermost blade ring 25 of the inner disc section with the innermost blade ring of the outer disc section on the side of said blade rings remote from the disc sections, a space being provided between said two blade rings in register with said opening, a regulating element 30 in said space to control the admission of elastic fluid to the blade ring surrounding the space, a turbine casing, and a bleeding chamber provided in said casing in communication with said opening. 35

4. In an elastic fluid turbine, two shafts for opposite rotation, a turbine disc on each shaft, blade rings on said discs so arranged as to form a radial flow blading for double rotation, one of said turbine discs comprising two separate annular sections spaced radially so as to form an 40 annular opening extending uninterruptedly all around between the outer periphery of the inner disc section and the inner periphery of the outer disc section, a substantially radially extending annular disc connecting the outermost blade ring 45 of the inner disc section with the innermost blade ring of the outer disc section on the side of said blade rings remote from the disc sections, a space being provided between said two blade rings in register with said opening, an axially adjustable regulating ring in said space to control the admission of elastic fluid to the blade ring surrounding the space, sealing fins on the outer periphery of said regulating ring to co- 55 operate with the inner periphery of said surrounding blade ring as well as with the inner periphery of the outer disc section, a turbine casing, and a bleeding chamber provided in said casing in communication with said opening. 60

5. In an elastic fluid turbine, two shafts for opposite rotation, a turbine disc on each shaft, blade rings on said discs so arranged as to form a radial flow blading for double rotation, one of said turbine discs comprising two separate annular sections spaced radially so as to form an 65 annular opening extending uninterruptedly all around between the outer periphery of the inner disc section and the inner periphery of the outer disc section, a substantially radially extending annular disc connecting the outermost blade ring of the inner disc section with the innermost blade ring of the outer disc section on the side of said blade rings remote from the disc sections, a space being provided between said two blade rings in 70 75

register with said opening, an axially adjustable regulating ring in said space to control the admission of elastic fluid to the blade ring surrounding the space, sealing fins on the outer periphery of said regulating ring to cooperate with the inner periphery of said surrounding blade ring, a stationary ring inserted between the

inner periphery of the outer disc section and said regulating rings, additional sealing fins on the regulating ring to cooperate with said stationary ring, a turbine casing, and a bleeding chamber provided in said casing in communication with 5 said opening.

RAGNAR OLOV JACOB MÖLLER.
